UNITED STATES PATENT OFFICE.

WARREN S. BELLOW'S, OF WORCESTER, MASSACHUSETTS.

WRENCH.

1,420,467.

Specification of Letters Patent. Patented June 20, 1922.

Application filed October 2, 1919. Serial No. 328,008.

To all whom it may concern:

Be it known that I, WARREN S. BELLOW'S, a citizen of the United States, residing in the city of Worcester, county of Worcester, 5 and State of Massachusetts, have invented certain new and useful Improvements in Wrenches, of which the following is a specification.

The present invention relates to tools, and 10 more particularly to that type known as wrenches.

An object of the present invention is to provide a wrench of the socket type and which has a pawl and ratchet movement, the 15 mounting of the pawl and the arrangement of the teeth of the ratchet being such as to direct stresses imparted upon the head of the wrench directly through the head and longitudinally of the pawl to offset any 20 tendency to distort or unseat the pawl and any tendency to break off the teeth of the ratchet.

Another object of the invention is to provide a ratchet wrench which may have interchangeable handles of various lengths.

Another object of the invention is to provide an improved structure of ratchet wrench the parts of which may be readily assembled and separated and wherein the stress im- 30 parted to the head of the wrench is directed as a longitudinal thrust against the handle.

With these and other objects in view, the invention consists in certain novel combina- 35 tions and arrangements of the parts as will more fully appear as the description pro-ceeds, the novel features thereof being pointed out in the appended claims.

For a full understanding of the invention, reference is to be had to the following de- 40 scription and accompanying drawings, in which:—

Figure 1 is a longitudinal section taken in an edgewise direction through a ratchet wrench constructed according to the present 45 invention.

Figure 2 is a similar view taken substantially on the line 2—2 of Figure 1.

Figure 3 is a transverse section taken on the line 3—3 of Figure 1.

Corresponding and like parts are referred to in the following description and indicated in all the views of the drawings by the same reference characters.

Referring to the drawing 1 designates a 50 hand-hold of any suitable configuration and length and which is provided upon what may be termed as its outer end with a shank por-

tion 2 formed by the reduction in width of the outer end of the hand-hold 1 to provide flat opposed seats or faces 3 and which shank 2 also has a transverse opening or 60 perforation 4 adapted to receive therein a screw 5 for holding a pair of side plates 6 and 7 against the opposite sides of the shank 2.

The side plates 6 and 7 constitute the component elements of a casing or outer handle portion which projects lengthwise from the outer end of the hand-hold 1 and forms therewith the handle or lever of the wrench. The plates 6 and 7, at their inner 70 ends are adapted to seat against the opposite flat faces 3 of the shank 2 and to engage at their inner edges against shoulders 8 formed at the juncture between the hand-hold 1 and the shank 2. The screw 5 passes through the plates 6 and 7 and the perforation 4, and has its threaded end in engagement with threads formed in one of the plates, such as the plate 7 as illustrated in Figure 2. It 80 is desirable to counter-sink the apertured portions of the plates 6 and 7 through which the screw 5 passes to maintain relatively flat and uninterrupted side faces to the handle or lever of the wrench. The plates 85 6 and 7 are detachably held together at their outer end portions by a second transversely extending screw 9 which is similarly counter-sunk and threaded in the plates. As shown in Figure 3, a rivet 10 or other similar fastening device may be secured through the side plates 6 and 7 and through a suitable aperture formed through the outer end of the shank 2 in spaced relation to the screw 5 for the purpose of bracing the side plates 6 and 95 7 on the hand-hold 1 and thus reinforcing the structure.

The outer end of the plates 6 and 7 are preferably enlarged and rounded to form a housing 11 into which is fitted a head 12. 100 The plates 6 and 7 are provided in opposite sides of the housing 11 with bearing openings 13 into which journal bosses 14 of the head 12 are adapted to engage, the bosses 14 being formed on opposite sides of the head 12 and serving as supports for the head in the sides of the housing. The head 12 is provided, between the plates 6 and 7 with peripheral teeth 15 which have radially extending sides 16 and inclined sides 17, the 110 latter diverging inwardly from the adjacent radial sides 16 and adapted to substantially meet the base of the next adjacent tooth. The throats formed between the teeth 15 are

thus provided with a flat radially extending wall and an outwardly inclined wall which merges into the base of the radial wall to form therewith an outwardly flaring notch 5 for the reception of a correspondingly shaped nose 18 of a pawl 19. The pawl 19 comprises a bar of suitable length which preferably slightly tapers from its inner end to its nose 18 and which has its inner end rounded to form a bearing surface 20 adapted to seat in a correspondingly formed notch or recess 21 in the outer end of the shank 2. The recess 21 and the bearing portion 20 are substantially semicircular in 10 form to provide a supporting and pivot seat for the pawl 19 to admit the swinging of the latter upon its bearing 20 and to support the pawl in all of its positions by a thrust extending longitudinally from end to end of 15 the pawl. The pawl 19 is preferably anchored in its recess or seat 21 by a U-shaped link or locking pin 22 having its ends engaged in recesses or apertures formed respectively in the bearing end 20 of the pawl 20 and the outer end of the shank 2, the said apertures or recesses being formed transversely in the pawl and the shank to receive the locking pin 22 by a transverse or lateral movement of the same. The closed end of 25 the locking pin 22 is counter-sunk or seated in the lateral faces of the pawl 19 and the shank 2, and the adjacent side plate 6 is adapted to bear against the locking pin 22 for maintaining it from accidental displacement. A spring 23 has one end seated in one 30 edge of the pawl 19 and its other end bearing against the adjacent edge portion of the casing formed by the plates 6 and 7. The plates 6 and 7 are formed with complementary 35 marginal flanges 24 adapted to meet when the plates are brought into closed relation and to maintain the plates throughout their lengths equidistantly spaced apart for housing the pawl and the head of the wrench. 40 The teeth 15 of the head holds the latter from moving out of the apertures 13 and serves as a means for centering the head within the housing. The spring 23 normally urges the pawl 19 to swing about its 45 pivot end 20 sufficiently to bind the nose 18 in the throat formed between adjacent teeth, the nose 18 having the beveled side 25 which, when the pawl is in locking position, lies in a plane substantially radial to the axis of 50 rotation of the head 12. As the flat side 25 of the pawl and the radial side 16 of the adjacent tooth are adapted to abut in face contact, any pressure exerted to effect the relative turning of the head 12 and the handle, 55 is distributed in a radial thrust from the head 12 to a longitudinal thrust through the pawl 19, and the latter thrust is taken up through the bearing pivoted end 20 of the pawl and the hand-hold 1. 60

65 There is therefore but little strain im-

posed upon the ratchet teeth 15, and the pawl 19, taking up the thrust longitudinally, is not subjected to any bending or twisting strain so that there is no tendency for the pawl to become broken or otherwise rendered useless. The spring 23 acts directly against the edge of the pawl to swing the latter about its bearing pivoted end 20 until the nose 18 engages in the throat between adjacent teeth. The spring thus merely directs the nose 18 of the pawl into proper position for subsequent locking, the flat faces 16 and 25 of the teeth and the pawl cooperating to wedge or urge the nose of the pawl toward the base of the teeth. 80

Having thus described the invention, what I claim as new and desire to secure by Letters Patent, is:-

1. In a wrench, in combination, a handle member, a socket head mounted to turn on the handle member and provided with ratchet teeth, and a pawl pivoted and seated at one end against the handle member at one side of the longitudinal axis thereof, said pawl being provided with a nose adapted to engage between the teeth of the socket head and having a flat face for surface contact with the adjacent toothed shoulder to wedge the nose of the pawl radially inward with respect to the socket head for transmitting strain radially through the head and longitudinally through the pawl. 90

2. In a wrench, in combination, a handle member, a socket head rotatably mounted on the handle member, and a pawl on the handle member, said socket head having peripheral ratchet teeth and said pawl being pivoted at one end on and seated at said end against the handle member for supporting the pawl and taking up thrust directed longitudinally thereagainst, said pawl being adapted to engage in the throats of said ratchet teeth and having a nose conforming to the contour of the throats, whereby strain exerted upon the head is directed radially therethrough and longitudinally through the pawl to said handle member. 105

3. A wrench comprising a hand-hold having a reduced end portion, a pair of complementary casing sections secured upon the reduced end portion and constituting a continuation of the hand-hold, said casing sections and said hand-hold having registering holes therein, fastening means passing through said holes and serving to hold said casing sections in abutting relation with one another and with said hand-hold, a socket member rotatably supported within the casing section and provided with peripheral ratchet teeth, and a pawl arranged within the casing sections and co-operating at one end with said ratchet teeth and pivotally mounted at its other end in the reduced end of said hand-hold. 115
